Primary Examiner — Ian Simmons*Assistant Examiner* — Shannon Morgan(74) *Attorney, Agent, or Firm* — Tillman Wright, PLLC;
James D. Wright; David R. Higgins(57) **CLAIM**

The ornamental design for a beverage coaster, as shown and described.

DESCRIPTION

FIG. 1 is a front perspective view showing my new design of a beverage coaster;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof; and,

FIG. 8 is another front perspective view showing my new design of a beverage coaster.

The broken lines in FIGS. 1, 2, 4–6, and 8 of the beverage coaster are for the purpose of illustrating environment, and form no part of the claimed design.
